UNITED STATES PATENT OFFICE.

FREDERICK B. CUSHMAN, OF NORTH BENNINGTON, VERMONT, ASSIGNOR TO H. T. CUSHMAN MFG. CO., OF NORTH BENNINGTON, VERMONT, A CORPORATION OF VERMONT.

DESIGN FOR A COMBINED SMOKER'S STAND AND TILTING TABLE.

Application filed March 14, 1927. Serial No. 21,129. Term of patent 7 years.

To all whom it may concern:

Be it known that I, FREDERICK B. CUSHMAN, a citizen of the United States, residing at North Bennington, in the county of Bennington and State of Vermont, have invented a new, original, and ornamental Design for a Combined Smoker's Stand and Tilting Table, of which the following is a specification, reference being had to the accompanying drawing, forming part thereof.

The figure is a perspective view of the smoker's stand with the tilting table in a horizontal position showing my new design.

I claim:

The ornamental design for a combined smoker's stand and tilting table substantially as shown.

FREDERICK B. CUSHMAN.
